AIR CONDITIONING APPARATUS

George M. Marr, New York, and Arthur P. Marr,
Brooklyn, N. Y., assignors to Air Conditioners,
Inc., New York, N. Y., a corporation of Dela-
ware

Application July 28, 1934, Serial No. 737,383

2 Claims. (Cl. 62—129)

The device, the subject of this invention we term an air conditioning apparatus and for the reason that it performs a number of the functions that are important in air conditioning.

5 Air conditioning in its broadest sense, consists of a number of treatments depending of course upon the initial condition of the air and the conditions required at the time that the conditioning or treatment is completed.

10 The present apparatus and the one which we were about to describe will accomplish a number of the desired purposes, such for instance as filtering the air if that is desired, of dehumidifying the air, of cooling it during dehumidification 15 and circulating it in a desired direction after it has been filtered, cooled and dehumidified. Our filtering is not in this instance air washing, but the primary filtration is for the purpose of removing the larger particles of dust or foreign 20 matter. The dehumidification also accomplishes purification as in the dehumidification cool dry surfaces are provided for the removal of the moisture or humidity and so in turn remove much of the foreign matter and smaller dust particles 25 in the air. The circulation is not only for the purpose of causing air to contact with the cooling and dehumidifying means, but is also for the purpose of distributing the air and we provide a directional device for the breaking of the 30 air streams as and when desired and thus we have described the objects of the invention, the construction of which will be set forth in the specification which follows and the accompanying drawings should be referred to for a complete 35 understanding of the specification.

In the drawings.

Figure 1 is a fractured front elevation of our device.

Figure 2 is a side elevation generally in section 40 of the completed device.

Figure 3 is an enlarged view of a damper mechanism.

Figure 4 shows an enlarged view of the shutter mechanism.

45 Figure 5 is a fractured sectional view showing a modified construction of a part.

Figure 6 shows a device of a somewhat modified construction and is a fractured side elevation, and

50 Figure 7 is a front elevation of the fins or projections.

Similar reference numerals indicate like parts in all the figures where they appear.

Our air conditioning device is entirely portable except that an electrical connection is re-

quired for operating the blower motor and as it is entirely portable, it is provided with a casing formed in two major parts. The part indicated at 1 we will refer to as the upper casing, and the part indicated at 2 we will refer to as the lower 5 casing.

Within the upper casing 1 we arrange a container 3, which may be adapted to receive solid CO₂ sometimes referred to as dry-ice, or water-ice or even cold water, and this container is provided with an efficient cover or closure 4, resting upon a gasket 5, the gasket in turn resting upon a lip or flange 6 of the container 3. We desire that this container be not in contact with the outside casing 1 and for that reason the container 3 is insulated from the casing 1 by the strips 7 and 8 and also by the insulation 9 which surrounds the three sides of the container 3. The cover 4 may be hinged as suggested at 10.

Secured to the bottom of the container 3 and extending downward in the casing 1, are a plurality of fins or plates. These fins or plates are relatively thin and are spaced apart a desired distance which will of course be determined by the size and capacity of our device. In Figure 1 a plurality of these plates are shown, only one of which is indicated by the reference character 11 and it will be noted in Figure 2, that these plates while extending more than the full width 15 of the container 3, are provided with a slot 12 into which the upper portion of the fan or blower 13 is introduced. The object of this construction is 20 best stated as follows:

The plates 11 are secured to the bottom of the container 3 in any manner, such as riveting as suggested at 14, soldering or in the manner shown in Figure 5. These plates conduct the heat from the air passing thru the fan to the refrigerant within the container 3 or as it might best be said, 40 the plates are continually retained cold by the refrigerant, so therefore air passing between the plates will be cooled to such an extent that the humidity in the air will be deposited upon the plates 11, to drop away therefrom as the moisture 45 builds up on the plates. The recess 12 in all of the plates makes it possible to provide an over-hanging means 11' at the intake side of the fan or blower, pre-cooling to an extent the air drawn into the device and materially increasing the efficiency of the device, both as an air cooler and a dehumidifier.

At the intake side of the fan we provide a screen 15 which may or may not be an air filter as shown in Figure 6. We prefer however that it 50

should to an extent at least filter the air. Forward of the fan is a baffle shown at 16 and intended to direct the air out of the horizontal to a vertical course, changing the direction of the air flow may and probably does reduce the speed and volume of the air, but it also accomplishes a more important purpose, it insures that all of the air discharged from the fan will pass between the fins or plates 11 and will because of the peculiar shape of the plates, remain in contact therewith an appreciable period of time, with the result that great cooling and dehumidification results.

Leaving the fan 13, the air travels upward directed by the baffle 16 and between the plates 11 and is discharged through a shutter aperture 17. In both figures the shutters are shown closed, but the dotted lines 18 in Figure 2 suggest that the shutters may be opened to direct the air as desired, the shutters being operated by the handle 19, operating a link 20 to which all of the shutters are connected by means of bell crank levers as shown at 21, so that the shutters operate simultaneously from the single lever 19.

The upper portion of the casing 1 is supported upon the lower casing member 2 as shown in Figure 2, but is insulated from the lower casing by a gasket 22 not only for the purpose of conserving energy, but for the purpose of quieting the device by dampening the mechanical vibrations. The lower casing member 2 is provided with a shelf 23 to which the upper casing member 1 is secured. The lower casing member projects upward slightly above the juncture of the two casings and the space 24 between these two casings allows any moisture of condensation that might collect on the upper casing to pass downward to the lower casing 23, from whence it is allowed to drip into a suitable container. If dry-ice is used as the refrigerant, it is desirable to introduce air into the refrigerant container 3 to insure controlled sublimation of the dry-ice. At 25 we show a channel and within the container 3 and local to the upper end of the channel is an adjustable damper member 26 as shown in Figure 3 and which controls the passage of air through the channel and into the container 3. The discharge of the gas is through the pipe 27 and this pipe is controlled by a valve 28, which valve will be allowed to remain open if dry-ice is employed, but will be closed if water-ice is employed, except at that time that it is desired to draw off the water.

At 29 we show a container for the water of condensation or dehumidification. This container is a drawer arranged in the lower casing member 2 and slideable upon suitable supports 30 and 31. This drawer is provided with a plurality of splash baffles as indicated at 32. The water from the ice melting in the container 3 may be discharged into the drawer 29 by operation of the plunger operated valve 28. The switch 33 is intended for the control of the fan motor 34 and to increase the flexibility and the satisfactory usefulness of our device, the fan motor may be a two speed or a multiple speed motor as suggested at the switch 33.

May we call attention to the angular arrangement of the upper front plate 36, the arrangement of which is not only for appearance, but is for the purpose of reducing discharge friction and for the further purpose of increasing the angles to which the shutters may direct the air.

May we also call attention to the continuation 75 of the discharge pipe 27 which is carried back

and forth behind the lower edges of the fan 13. When water ice is used possibly no appreciable cooling of the air will result from this circuitous arrangement of the pipe 27, but when dry ice is used the passage of the gas through this pipe will assure that all of the cooling effort contained even in the gas, will be removed and the gas will be discharged only after its usefulness has been exhausted.

To obtain the highest possible efficiency, a direct metallic contact of the plates 11 with a refrigerant is desired. We may accomplish this as previously stated, but another way and that shown in Figure 5 is to have the plates 11 actually pass through the bottom of the container 3. Each plate is then bent over at the top as indicated at "b" and may then be secured in place by soldering, thus the refrigerant rests immediately upon the plates and the maximum cooling effect is obtained.

In Figure 6 we show a device of somewhat different construction. In this device the casing 31 is continuous, that is it is not a two part casing. The front panel 33 is however arranged at an angle at the point where the air is discharged. The fan or blower 39 in this construction is arranged at an angle and this makes it possible to employ continuous fins or plates as shown at 40, these plates being secured to the refrigerant container 41 in any manner desired, but it is very desirable that the connection between the fins or plates 40 and the refrigerant container, be a good thermal conducting joint.

The plates or fins, an end elevation of which is shown in Figure 7, are corrugated as indicated at 42, and while such corrugations will slow down the passage of air to a slight extent, they will also assure that the air will contact with the plates and that no air film will form on the plates. As a result of recent experimentation, we are led to believe that corrugated fins or projecting plates are very desirable and for that reason they may be employed with the device shown in the earlier Figures 1 and 2. The fan or blower motor 39 when arranged at an angle should be provided with a thrust bearing as indicated at 43.

The space 44 between the refrigerant container 41 and the outer wall of our cabinet is in this construction closed by means of a member 45 of a desirable shape. In closing this space we depend upon dead or impounded air as the insulating means, and such insulating means would be arranged at all sides of our refrigerant container 41 except the bottom thereof. At 46 we show an air filter consisting of two sheets of screen with a filtering medium arranged therebetween. This filtering medium may be curled hair, steel wool or any other type of filter and is shown to indicate that a filter may well be employed with our device.

The drain pipe 47 is in this construction arranged in front of the blower 39 and between the blower and the fins or plates 40 and may be circuitous in this space in any direction, and while the arrangement of this tubular member 47 is desirable with water-ice, it is particularly desirable if dry-ice is used, as it assures that the gas of sublimation will be retained until all of its desirable cooling effect is removed therefrom.

In Figure 1 we show one horizontal run of the drain pipe extending behind the lower portion of the fan blades, but in this Figure 6 we indicate that we may have a plurality of horizontally extended pipe lines, in fact we have shown four

such lines as indicated at 49, 50, 51 and 52. The horizontal pipes 49 and 50 are connected at one end by means of a short length of pipe or nipple 53, and a longer pipe 54 connects one end of the 5 horizontal pipe 50 with the next successively horizontal pipe 51.

In the short nipple 55 which connects the pipe 51 and 52, we may introduce a riser 56 arranged parallel to the drain pipe 47. This riser extending upward into the refrigerant chamber 41.

When water-ice is used as the refrigerant or when a liquid is contained in our device, the valve 28 will be retained closed and under this condition the water from the ice will circulate through 15 the pipes 47, 49 to 56 and we have found that when the air delivered by the fan or blower 39 is quite warm, a very active circulation and recirculation will take place in these pipes.

When dry-ice is used as the refrigerant, we 20 recommend that the uppermost open end of the pipe 56 be closed and the valve 28 allowed to remain open. This will assure that the gas of sublimation is retained in the pipe run for a suitable length of time as above referred to.

25 As this device shown in Figure 6 is smaller and somewhat lighter than the device shown in Figures 1 and 2, we may omit the casters or rollers shown in Figures 1 and 2 and substitute balls or ball shape metallic members or even rubber foot 30 pieces as shown at 48. The operation of this device is in all respects similar to the device previously described. However even though a number of structural changes or modifications are made,

they are intended to increase rather than decrease the efficiency.

The plates 11 may be extended downward for a greater distance than that shown.

The shape of our device may be changed at 5 will and the parts arranged to accommodate such changes.

We have shown but four shutter plates 18, but the number of plates may be increased or decreased as may the area thereof. 10

Having carefully and fully described our invention, what we claim and desire to obtain is:

1. An air conditioner comprising a casing, a blower arranged therein, a refrigerant container arranged therein, a plurality of heat conducting 15 plates secured to said refrigerant container and projecting into the path of both the intake and exhaust of said blower.

2. An air conditioning device comprising a container, an air blower arranged therein, a refrigerant container within said casing and insulated therefrom, a plurality of thermal conductors secured to said refrigerant container, means for directing the air from the blower in contact with said thermal conductors, and means for directing the air upon its discharge from the said casing, and means for collecting the water of dehumidification from said thermal conductors and a tubular member connected to said refrigerant container and passing through certain of said 30 conductors. 25
